UNITED STATES PATENT OFFICE

WILLARD P. ZIMMERMAN, OF MUNCIE, INDIANA, ASSIGNOR TO HEMINGRAY GLASS COMPANY, OF MUNCIE, INDIANA, A CORPORATION OF KENTUCKY

DESIGN FOR A BOTTLE OR SIMILAR ARTICLE

Application filed March 6, 1931. Serial No. 38,979. Term of patent 14 years.

To all whom it may concern:

Be it known that I, WILLARD P. ZIMMERMAN, a citizen of the United States, residing at Muncie, Indiana, have invented a new, original, and ornamental Design for a Bottle or Similar Article, of which the following is a specification, reference being had to the accompanying drawings, forming part thereof.

In the drawings

I claim:

The ornamental design for a bottle or similar article substantially as shown and described.

In testimony whereof I have hereunto set my hand.

WILLARD P. ZIMMERMAN.
